DESIGN FOR A DOLL'S SULKY

Harry B. Louer, Chicago, Ill.

Application February 15, 1945, Serial No. 117,975

Term of patent 3½ years

(Cl. D34—15)

To all whom it may concern:

Be it known that I, Harry B. Louer, a citizen of the United States, residing at Chicago, in the county of Cook and State of Illinois, have invented a new, original, and ornamental Design for a Doll's Sulky, of which the following is a specification, reference being had to the accompanying drawing, forming a part thereof.

Fig. 1 is a front view of a doll's sulky showing my new design;

Fig. 2 is a rear view thereof;
Fig. 3 is a side view thereof; and
Fig. 4 is a top plan view thereof.

I claim:

The ornamental design for a doll's sulky, substantially as shown.

HARRY B. LOUER.
